COMBINED HEIGHT AND WEIGHT MEASURING DEVICE OR SIMILAR ARTICLE

Hubert M. Giepen, Cohasset, Mass., assignor to
Red Mill Company, Boston, Mass., a partnership

Application June 29, 1953, Serial No. 25,697

Term of patent 14 years

(Cl. D52—10)

To all whom it may concern:

Be it known that I, Hubert M. Giepen, a citizen of no country, residing at Cohasset, county of Norfolk, and Commonwealth of Massachusetts, have invented a new, original, and ornamental Design for a Combined Height and Weight Measuring Device or Similar Article, of which the following is a specification, reference being had to the accompanying drawings, forming a part thereof.

Fig. 1 is a front elevation of a combined height and weight measuring device showing my new design;

Fig. 2 is a side elevation thereof; and

Fig. 3 is a top plan view drawn to a larger scale than Fig. 1.

I claim:

The ornamental design for a combined height and weight measuring device or similar article, substantially as shown.
